CLAIM

The ornamental design for a magnetic toy car, as shown and described.

DESCRIPTION

FIG. 1 is a perspective view of a magnetic toy car showing my new design, including two car halves separably joined together on opposite sides of a platen, such as a windshield, by magnetic force, the platen forming no part of the claimed invention;

FIG. 2 is a side view thereof;

FIG. 3 is an opposite side view thereof;

FIG. 4 is a top view thereof;

FIG. 5 is a bottom view thereof;

FIG. 6 is a front view thereof;

FIG. 7 is a rear view thereof;

FIG. 8 is another perspective view thereof, showing a pair of earth magnets mounted in and carried by respective halves of the car; and,

FIG. 9 is another top view thereof, showing the relative position of the magnets illustrated in FIG. 8.

The broken lines shown in FIGS. 1-9 are for illustrative purposes only and form no part of the claimed design.
